JEREMIAH R. LITTLE, OF JAMAICA PLAINS, MASSACHUSETTS.

Letters Patent No. 94,965, dated September 21, 1869.

IMPROVEMENT IN METALLIC BUTTON-HOLE OR CLASP.

The Schedule referred to in these Letters Patent and making part of the same.

To all persons to whom these presents may come:

Be it known that I, JEREMIAH R. LITTLE, of Jamaica Plains, of the county of Norfolk, and State of Massachusetts, have invented a new and useful Button-Clasp; and do hereby declare the same to be fully described in the following specification, and represented in the accompanying drawing, which is a side view of it.

It is particularly intended to be affixed to the end of a suspender-strap, to constitute an elastic metallic button-hole or clasp, to embrace a button in the manner in which an ordinary button-hole does, when in engagement with such.

The article is to be made of a piece of elastic wire of the proper length. In constructing it, the wire, near its middle, is to be bent around so as to form an elongated eye, as shown in *a*, with the two legs or parts of the wire crossing one another at the middle of the lower part of the said eye.

Next, the two legs are to be bent down parallel, or about so, with each other, and a little apart, and at or about at right angles with the eye.

Next, they are to be crossed on one another, as shown at *e*, and afterward bent around up to the eye *a*, in manner as represented at *d d'*.

Finally, they are to be fastened at their extremities to the bottom of the eye *a*, either by solder or otherwise, (the whole being as exhibited in the drawing,) so as to form a button-hole, *c*, with elastic or spring sides.

A person, by clasping the two parts *d d'* between

the thumb and second finger of his hand, and pressing the said parts toward each other, will easily be able to expand the button-hole or opening *c*, so as to enable a button to be passed through it.

By removing the pressure of the thumb and finger from the parts *d d'*, the sides of the button-hole will collapse or close, on the eye or fastening of the button.

The removal of the button-clasp from a button may be effected by first simply pressing together the parts *d d'*, so as to extend the button-hole sufficiently, and next drawing the clasp off the button.

The said new manufacture, though designed specially for suspender-straps, may also be used with various other straps, or articles which, when in use, may require to be buttoned to something else.

I claim as of my invention the following, that is to say—

The button-clasp, as made of elastic wire, or its equivalent, bent or curved so as to form an expansive eye or button-hole, *c*, to operate substantially as set forth.

Also, a button-clasp, as made of elastic wire, or its equivalent, bent or curved so as to form an expansive eye or button-hole, *c*, to operate substantially as set forth, and a loop or eye, *a*, for connecting the article to a strap.

J. RUSSELL LITTLE.
